UNITED STATES PATENT OFFICE.

JOSEPH N. ARONSON, OF LONDON, ENGLAND.

ELECTRIC BRUSH.

SPECIFICATION forming part of Letters Patent No. 279,315, dated June 12, 1883.

Application filed July 14, 1882. (Model.) Patented in England December 21, 1881, No. 5,601; in France June 21, 1882, No. 149,705, and in Belgium June 24, 1882, No. 58,297.

To all whom it may concern:

Be it known that I, JOSEPH NORMAN ARONSON, a citizen of the United States, but temporarily residing in Old Broad Street, in the 5 city of London, England, have invented a new and useful Improvement in Electric Brushes; and I do hereby declare that the following is a full, clear, and exact description of the same.

My invention relates to electrical brushes 10 for the application of currents of electricity to the skin of the head and roots of the hair for promoting the growth of the hair and for curative and remedial purposes.

My invention relates to the combination, 15 with a brush, constructed substantially as hereinafter described, for the transmission of electric currents to the skin and roots of the hair, of an induction-coil and battery for the generation of the currents, and to the peculiar 20 construction of the brush for the purposes above mentioned.

The brush is made principally of animal-bristles, having intermixed therewith two sets of metallic-wire bristles, insulated from one 25 another in the brush-back in which they are set, the said metallic wires being preferably in the form of loops or staples, the limbs of which pass through the back and form the bristles. The two sets are respectively in 30 connection with the two ends of the secondary wire of the induction-coil, which is arranged within the hollow brush-back, the primary wire being connected with the poles of the battery, which might also be contained within the 35 brush-back or be placed in the handle of the brush, if provided with one. The coil may be provided with a regulator consisting of a tube arranged to slide in and out over the bundle of iron wire in the induction apparatus, and projecting through the side or end of the brush-back, whereby it may be readily 40 adjusted to vary the strength of the current; but this is not necessary, and I prefer to dispense with it. The coil is provided with the usual vibrating current-breaker.

Figure 1 is a back view of a hair-brush, with the inclosing-cover removed, showing the battery induction-coil and connections in position. Fig. 2 is a view of the stock, with the

plate on which the battery and coil are fixed 50 removed, showing the arrangement of the metallic bristles only; and Fig. 3 is a cross-section of the brush complete.

a is the induction-coil, and *b* the battery, of the kind known as a "medical Leclanché," 55 both fixed on a wooden or other plate, *c*, fixed to the stock *d*.

e e' are the connections of the primary circuit of the coil with the poles of the battery.

f is a spring-contact maker in the circuit of 60 the primary wire, provided with a push-piece, *g*, which projects through a hole in the inclosing-cover in position to be depressed by the finger, in order to close the circuit only when the brush is held in the hand for use. 65

h is the usual vibrating current-breaker of the induction-coil.

i i' are the connections of the secondary circuit, with the wires *k k'*, to which the two sets of wire bristles *l l'*, forming the poles, are attached in the ordinary way of brush-making by drawing bent loops of wire through holes in the stock. These two sets of wire bristles are insulated from one another by the wooden 70 or other stock in which they are fixed. 75

m are the ordinary animal-bristles.

n is the box-cover of the back inclosing the battery and coil.

Fig. 4 is a face, and Fig. 5 an end, view of a flesh-brush in which the wire bristles are 80 replaced by rounded metal strips *o o'*.

In practical operation the brush is held in the hand, with one finger thereof pressed upon the contact-maker *g*, and therefore when the brush is applied to the head an electric circuit is formed through the moist skin between the wires or points *l l'*. The electric current is thus caused to traverse the roots of the hair, and produces a tonic and highly-beneficial effect, preventing falling of the same, promoting its growth and increasing the oily secretions, which render it flexible, smooth, and glossy. 85 90

Having thus described my invention, what I claim as new is—

1. The combination, with a brush having wire points or plates arranged among its bristles, of a battery, an induction-coil, and a cir- 95

cuit-closer having a push-piece extending through the cover of the brush, substantially as herein shown and described.

2. The combination, with a brush provided with the two sets of insulated wire bristles or points $l\ l'$, of the induction-coil a , the battery b , the circuit-closer $f\ g$, the current-breaker h , and the connections $e\ e\ e'$ and $i\ i'$, substantially as herein shown and described.

The foregoing specification of my improvement in electrical brushes and combs signed by me.

JOSEPH NORMAN ARONSON.
